UNITED STATES PATENT OFFICE.

MAX POETZSCH, OF CLIFTON, NEW JERSEY.

APPARATUS FOR BLEACHING, DYEING, &c.

1,383,021.

Specification of Letters Patent. Patented June 28, 1921.

Application filed November 6, 1919. Serial No. 336,005.

To all whom it may concern:

Be it known that I, MAX POETZSCH, a citizen of the United States, and a resident of Clifton, in the county of Passaic and State 5 of New Jersey, have invented a new and Improved Apparatus for Bleaching, Dyeing, &c., of which the following is a full, clear, and exact description.

This invention relates to an apparatus 10 which eliminates or avoids permanent creases in a piece or string of cloth when dyeing, bleaching or washing the same, and also shortens the process involved.

Another object of the invention is to provide a construction wherein strings or strips 15 of cloth are automatically changed and refolded in a more or less continuous action during the dyeing, bleaching or washing operation so that permanent creases will not 20 be formed in the cloth.

A further object of the invention, more specifically, is to provide an apparatus with 25 a roller which may be formed with raised and depressed portions alternately in a scalloped formation, and a spreading or refolding member co-acting therewith for causing the cloth to be refolded as it passes over the roller and thereby prevent the formation of permanent creases during the operation of 30 the apparatus, whether it be dyeing, bleaching or washing.

In the accompanying drawings:

Figure 1 is a longitudinal vertical section 35 through an apparatus disclosing an embodiment of the invention, same being taken on line 1—1 of Fig. 2.

Fig. 2 is a top plan view of the apparatus shown in Fig. 1.

Fig. 3 is a sectional view through Fig. 4 40 on line 3—3, same showing a slightly modified form of the invention.

Fig. 4 is a sectional view through Fig. 3 on line 4—4.

Fig. 5 is a top plan view of one end of the 45 apparatus shown in Fig. 3.

Fig. 6 is a fragmentary top plan view of an oscillating member used in the structure shown in Fig. 3.

Fig. 7 is a fragmentary top plan view of a 50 stationary guide used in the structure shown in Fig. 3.

Fig. 8 is a sectional view through Fig. 9 55 on line 8—8, the same showing a further modified form of the invention to that shown in Fig. 3.

Fig. 9 is a section through Fig. 8 on line 9—9.

Fig. 10 is a top plan view of one end of the apparatus shown in Fig. 8.

Fig. 11 is a fragmentary sectional view 60 through a slightly modified form of feeding roller to that shown in Fig. 2, the same being on an enlarged scale.

Referring to the accompanying drawings by numerals 1 indicates a support of any desired kind for a container 2 which is substantially segmental in cross section as shown in Fig. 1; this shape being provided merely for the purpose of convenience. Arranged in the container 2 is a supply of liquid 65 which may be dye, a bleaching compound or washing liquid, said liquid being prepared for acting on the string of cloth passing therethrough for producing the results desired. Arranged above the container 70 2 is a comparatively large driving roller 4 accommodating the strips or strings of cloth 5. Any number of pieces of cloth may be caused to move over the roller 4, preferably a comparatively large number so that 75 a large quantity of cloth may be treated when used in any of the apparatuses mentioned, namely dyeing, bleaching or washing machines, a plurality of pieces of cloth of any length, as for instance thirty yards 80 connected in strings so as to make continuous belts. As many of these strings are placed on the roller or drum 4 as the same will accommodate, the strings being arranged so that most of the cloth will be in 85 folds 6 in the container 2 as shown in Fig. 1, while the upper part of the cloth will pass over the drum or roller 4, refolding roller 7 and spreading member 8. A guide 9, similar to that shown in Fig. 7, is used for maintaining the strings separate as they leave 90 the liquid. These guides are made from a suitable frame 10 having partitions 11, said frame being secured in place on the container 2 by any desired means, as for instance screws. Preferably a perforated division board 12 is provided near the wall 13, though this is not always necessary. The 95 refold roller 7 is what may be termed fluted as it is formed with reduced portions or 100 sections 14 and with bulged or raised sections 15 alternately for the full length of the roller. This roller carries a suitable supporting shaft to which the sprocket 16 is secured, said sprocket accommodating a chain 105 110

17 passing over sprocket 18. Sprocket 18 is rigidly secured to shaft 19 connected with the drum 4 and with a driving pulley 20. Pulley 20 accommodates a belt 21 which 5 passes over a small pulley 22 rigidly secured to the shaft 23 extending through the spreading member 8 to which it is rigidly secured. The member 8 is substantially diamond shape in cross section as shown in 10 Fig. 1 with the points rounded and with alternate depressions 24 and raised portions 25 arranged in line with the depressions and raised portions 14 and 15. The belt 21 is arranged so as to drive the spreading member 8 at different speeds under different circumstances. Usually when the spreading member is moving with the goods it moves slightly faster than the goods, but when moving in a direction opposite the direction 15 of the movement of the goods it moves much slower than the goods. By reason of the chain 17 it will be seen that the roller 7 moves always in one direction with the drum 4, and by reason of the size of the 20 sprocket wheels 16 and 18 and roller 7 has the same peripheral speed as the drum 4. If desired the peripheral speed of the roller 7 may be slightly more than the drum 4 so as to assist in spreading as well as refolding 25 the cloth. As the roller 7 rotates and as the spreading member 8 rotates the cloth will have a tendency to move over the reduced portions 14 and 24 upwardly toward the raised portions 15 and 25 and thereby 30 become folded longitudinally at a new place. When any particular point of the string gets around again to the roller 7 it will not be folded at the same place that it was before, caused by the tendency of the cloth to climb 35 to the highest point, and consequently permanent creases will be prevented. After the various strings 5 of cloth have been arranged in position the apparatus is started and the strings are gradually moved 40 through the liquid continuously for any desired length of time, as for instance from one hour to six or eight hours, according to the liquid used, the cloth and other controlling circumstances. The apparatus may 45 be driven by any suitable source of power which is preferably connected to the driving pulley 26 secured to shaft 19.

In Figs. 3 to 6 inclusive will be seen a slight modified form of the invention in 55 which the different construction consists in the use of a special form of spreading means 27. The spreading device 27 consists in a flat section 28 having a scalloped edge 29 for causing a movement of the cloth laterally of its direction of travel. To better accomplish this result the spreader is connected to a rotating disk 30 through a link 31. The disk 30 is secured to shaft 32 which carries a worm wheel 33 meshing with the 60 worm 34. The worm 34 is secured to the

shaft 35, said shaft carrying a sprocket 16 and the re-folding roller 7. In this way as the drum 4 and roller 7 are rotated, the spreader 27 will be moved back and forth, said movement being preferably slow compared to the rotary movement of the roller 7. 70

In Figs. 8 to 10 inclusive will be seen a further modified form of the invention in which the modification consists in the use of a modified form of spreader 36. This 75 spreader consists of a flat plate or board 37 having a plurality of spaced eyelets 38. The board 37 is supported on a suitable frame work 39 by pivotally mounted connecting links 40 and 41 whereby as the board 37 and 80 associate parts are moved back and forth the board will be moved up and down also. The length of the links 40 and 41 and the spacing of the eyelets 38 are such that the center of the eyelet will move from the center of 85 the enlarged portion 15 to the center of the reduced portion 14 of the roller 7 during the operation of the machine. This back and forth motion of the eyelet will assist the roller 7 in refolding the string continuously 90 so that the string or cloth will not be folded twice in the same place and thereby will not form permanent creases. The means for reciprocating the spreader 36 may be any suitable means, but preferably it is the same arrangement of eccentric and link structure described in respect to Figs. 4 and 5 so that 95 it will need no additional description.

In Fig. 11 will be seen a preferred form of roller 7. It is, of course, evident that the 100 roller 7 could be turned from one piece of wood or other material, but preferably it is constructed as shown in Fig. 11, wherein there is provided a central base 42 which may be wood or other material and extends 105 for the full width of the vat 2. This base is provided with a swelled section 43 adjacent each bulged or raised portion 15. Each of the swelled sections 43 is provided with stepped formations 44 and 45 and a central 110 raised portion 46 which receives the central block 47, which block is wedge shape. On each side of the block 47 a number of disks 48 are provided, each disk being successively smaller as they recede from the block 47 so 115 as to produce the rounded or bulged portion 15. The reduced portion 14 is preferably made from a solid piece of material, as for instance wood, though if desired it could be made from other material. Preferably the 120 central portion 44 and the blocks 47 are secured to the base 42 in any suitable manner, as for instance by screws or keys, while the disks 48 are permitted to freely rotate on the stepped formations of the base. The base 125 42 may be connected with a rotating mechanism as shown in Figs. 2, 5 and 10, or may be held stationary so that the cloth will rotate the disk. When the base 42 is held stationary it is preferably positioned so that 130

the cloth will first engage the disk near the sharpened end 49 of the block 47 whereby as it passes over the disk toward the roller or drum 4 it will be spread positively so that it 5 must refold in a different manner as it passes over the drum 4 and also through the remaining part of the operation.

What I claim is:

1. An apparatus for bleaching, dyeing, etc., comprising a liquid containing vat, means for feeding cloth into the vat and removing the cloth from the vat in a continuous movement, and means for longitudinally refolding the cloth each time it passes 15 over said feeding means.

2. An apparatus for bleaching, dyeing, etc., comprising a vat containing a liquid for treating strings of cloth, means arranged above the vat for receiving said strings 20 of cloth, a scalloped refolding roller, said refolding roller rotating during the operation of the apparatus, and means for guiding said strings of cloth from the vat to the refolding roller.

25 3. An apparatus for bleaching, dyeing, etc., comprising a vat containing liquid, a drum arranged above one edge of the vat for moving a string of cloth through the vat, means for rotating said drum, a refolding 30 roller round in cross section at all points, said refolding roller having alternate raised and depressed portions merging into each other, means for rotating said refolding roller so that the same will have substantially the same peripheral speed as the drum, and means for guiding a string of cloth 35 from the vat to the refolding roller.

4. An apparatus for bleaching, dyeing, etc., comprising a vat for containing liquid, 40 a power drum arranged above and adjacent one edge of the vat, said drum being adapted to receive a plurality of strings of cloth and to gradually move them through said liquid, a roller adapted to refold the cloth 45 longitudinally arranged above and substantially in line with the opposite edge of the vat to the drum, a spreader arranged between the roller and the vat, and means for guiding the cloth from the vat to the 50 spreader.

5. An apparatus for bleaching, dyeing, etc., comprising a vat, a drum for moving strings of cloth through the vat, a refolding roller having substantially the same peripheral speed as the drum for refolding said strings, a spreading member formed with a corrugated or waved edge, said spreading member being arranged between the refolding roller and the vat, and means for 55 moving said spreading member back and forth in a direction parallel with the refolding roller.

6. An apparatus for bleaching, dyeing, etc., comprising a vat for containing liquid, 60 a rotatable drum for receiving and moving

strings of cloth so that they will gradually pass through said vat, a corrugated or fluted roller arranged adjacent the drum acting as a refolding roller, and a reciprocating spreader arranged with a fluted or corrugated edge for moving the strings of cloth back and forth as they pass to the refolding roller. 70

7. An apparatus for bleaching, dyeing, etc., comprising a vat containing liquid, a 75 rotatable drum arranged above the vat for receiving and moving a plurality of strings of cloth through said liquid, a refolding roller for assisting in moving said strings, and spreading means for causing the strings 80 of cloth to move laterally back and forth across said refolding roller and thereby be folded longitudinally at different places each time it passes thereover, said spreading means comprising a reciprocating supporting member the reciprocations of which are substantially parallel with the refolding roller, and a plurality of eyelets arranged on said reciprocating member, there being one eyelet for each string of cloth passing 85 over the refolding roller.

8. An apparatus for bleaching, dyeing etc., comprising a vat for receiving liquid, means for moving strings of cloth through said liquid, said means including a refolding 90 roller above the vat adjacent one edge, and spreading means for causing the cloth to travel over the roller at different points consequently to be folded longitudinally in a different place each time it passes over the 95 roller so as to eliminate permanent creasing of the cloth, said spreading means comprising a plate extending substantially parallel with the refolding roller, a plurality of links pivotally connected to a stationary support 100 and to the plate, means for reciprocating the plate whereby as the plate moves back and forth it will also move up and down, said plate being formed with a plurality of openings, there being one opening for each string 105 of cloth.

9. An apparatus for bleaching, dyeing, etc., comprising a vat for containing liquid, means for moving strings of cloth through said liquid, the means including a corrugated 110 or fluted rotatable roller, a spreading member for spreading the cloth as it passes over said roller, and means for moving said spreading member, said spreading member comprising a stationary support, a plurality of links, a reciprocating plate, means for pivotally connecting the ends of said links to said plate whereby as the plate is reciprocated it will also move up and down with a parallel motion, and a plurality of eyelets 115 arranged in said plate, said eyelets being spaced apart the same distance as the corrugations or flutes in the roller and the reciprocation of the plate being such as to move the respective eyelets from the low 120 to the high position as the plate moves up and down. 125

65 a rotatable drum for receiving and moving

point of the corrugations to the high and then back successively.

10. An apparatus for bleaching, dyeing, etc., comprising a vat, a drum for moving a string of cloth through the vat, a refolding roller for spreading the cloth so as to cause a refolding, said roller comprising a base, and a plurality of pairs of groups of rotatable disks arranged on the base, the groups being spaced apart and bulged or rounded.

11. A refolding roller comprising a base, and a plurality of series of bunches of disks, and a supporting base for loosely supporting the disks whereby they may be independently rotated.

12. A refolding roller comprising a base having a plurality of swelled portions

formed with stepped surfaces, a set of disks loosely mounted on each of said surfaces, a wedge shaped block arranged between each group of disks, there being one wedge shaped block and a group of disks for each bulged or waved portion of the roller.

13. A refolding roller formed with a plurality of bulged portions and a plurality of reduced portions, said roller being formed with a base, a separate section forming each of the reduced portions, and a central block, a group of disks on each side of the central block forming the bulged portions, said disks being independently rotatably mounted on the base.

MAX POETZSCH.
